UNITED STATES PATENT OFFICE.

JOSEPH J. COHN, OF NEW YORK, N. Y.

DESIGN FOR AN AUTOMOBILE-HORN.

41,154.

Specification for Design.

Patented Feb. 7, 1911.

Application filed December 10, 1909. Serial No. 532,499. Term of patent 7 years.

To all whom it may concern:

Be it known that I, JOSEPH J. COHN, a citizen of the United States, residing at the borough of Manhattan, in the city, county, and State of New York, have invented a certain new, original, and ornamental Design for Automobile-Horns, of which the following is a specification, reference being had therein to the accompanying drawings, forming a part thereof.

Referring to the accompanying drawings, Figure 1 is a front view of an auto-

mobile horn showing my new design, and Fig. 2 is a side view thereof.

I claim:

The ornamental design for an automobile horn as shown.

In witness whereof, I have hereunto affixed my signature, this 6th day of December, 1909, in the presence of two witnesses.

JOSEPH J. COHN.
